UNITED STATES PATENT OFFICE

2,089,246

SKIVING MACHINE

Clifton T. Batchelder, Haverhill, Mass., assignor
to United Shoe Machinery Corporation, Pat-
erson, N. J., a corporation of New Jersey

Application October 28, 1936, Serial No. 108,048

7 Claims. (Cl. 69—16)

This invention relates to skiving machines and is herein illustrated as embodied in a machine for cutting on an angle a strip from a piece of flexible sheet material, for example for cutting off the toe end of a vamp on a bevel.

In the manufacture of boots and shoes in which square-ended vamps with tips stitched to them are used, it is customary in some factories to die out the vamp from patterns which are correct for the shortest tips to be used. The square end of the vamp is skived in any event so as to prevent the formation of an objectionable ridge in the finished shoe along the locality of its attachment to the tip; and in the case of a long tip, where the extent of the overlap would be objectionable, it is customary to cut off on an angle a strip from the square end so as to produce a shorter vamp having a skived toe end.

Machines for performing this cutting-off operation commonly comprise among other elements a knife, a feed roll, a member for supporting the strip which is to be cut off, an edge gage and a presser foot for holding the material against the feed roll.

According to one feature of the present invention, a controller is provided for the strip which is being cut off, said controller extending over the strip-supporting member, being carried by the presser foot and preferably being slidably received in a recess or socket in the edge gage to permit adjustment of said gage. With such a construction, the strip is properly guided, and the rear walls of both the presser foot and the gage may be maintained in a common plane passed vertically and longitudinally through the feed roll.

This and other features of the invention, including certain details of construction and combinations of parts, will be described as embodied in an illustrated machine and pointed out in the appended claims.

Referring to the accompanying drawings,

Fig. 1 is a front elevation of a portion of a machine in which the present invention is embodied;

Fig. 2 is an end elevation of a portion of the machine;

Fig. 3 is a section on the line III—III of Fig. 1;

Fig. 4 is a view partly in section and partly in elevation showing a piece of work in process of being operated upon;

Fig. 5 is a perspective of the presser foot and the edge gage in extended relation;

Fig. 6 is an end elevation of the presser foot; and

Fig. 7 is an end elevation of the edge gage.

The illustrated machine is designed to be capable of use, as may be desired, both for cutting off the end of a vamp or other piece of sheet material on a bevel and for beveling or skiving the margin of a piece of sheet material. The machine, like the machine of United States Letters Patent No. 1,342,430, granted June 8, 1920, upon an application filed in the name of Newell V. Dyer, comprises a feed roll 11, a spring-pressed rotary feed disk 13, a rotary disk knife 15, a presser foot 17, an edge gage 19 and a supporting member or table 21. The construction and mounting of the feed disk, feed roll, knife and presser foot are substantially like the construction and mounting of the corresponding members of the machine of United States Letters Patent No. 1,866,918, granted July 12, 1932, upon an application filed in the name of Milton H. Ballard.

The feed roll shaft (not shown) is rotatably mounted in a bearing member 23 which is adjustable horizontally in a carrier 25, said carrier being adjustable in a curved guideway in a stationary member 27 by actuating a link 29 by means of a treadle (not shown). The bearing member 23 carries a casting 31 by which the feed disk shaft is carried; and to this casting is adjustably fastened a bracket 33 by which the presser foot 17 and edge gage 19 are indirectly carried. Consequently, when the feed roll 11 is adjusted angularly to vary the angle of the scarf produced, the feed disk, the presser foot and the edge gage are adjusted with it. The feed disk, knife and feed roll are rotated continually as in the machine of the Ballard patent. As thus far described, except for the table 21, the machine may be like that of the Ballard patent to which reference is made for details not herein shown and described. It will be understood that the work is fed away from the observer, as viewed in Fig. 1, by the action of the feed disk 13 and the feed roll 11 with the part of the work being operated upon passing beneath the presser foot 17 and with the edge of the work bearing against the edge gage 19.

The table or supporting member 21 is provided for supporting the strip which is cut off. This table is adjustably mounted at the upper end of an angle iron 35 by means of a cap screw 37 which passes through a slot 39 in the angle iron and is threaded into the downwardly extending stem of the table 21. The lower horizontal arm of the angle iron 35 is adjustably fastened by a screw 41 which passes through a slot 42 in the arm and is threaded into one member 43 of a clamp, the other member being indicated at 45.

A long screw 47 which passes loosely through a bore in the member 43 and is threaded in the member 45, clamps the two members in adjusted position upon a dovetailed guide 48 formed 5 on the lower portion of the bearing member 23 in which the feed roll shaft is mounted. It is thus possible to adjust the support or table 21 in three directions. The supporting surface of the table 21 (Fig. 2) is cylindrical, and its curvature 10 corresponds to that of the surface of the feed roll. The table, however, (Fig. 4), is adjusted into a position in which its periphery extends slightly beyond that of the feed roll so that, when a piece of work 100 is being operated upon, there 15 is a slight upward bend in the work at the point 200 to ensure that the knife shall make a clean cut. The rear edge 49 of the table 21 lies in a vertical longitudinal plane passed through the axis of the feed roll; and the forward point on 20 the edge of the rotary knife lies close to this plane. With the parts in the positions shown, the piece of work will be severed on a bevel, as shown in Fig. 4, the edge of the bevel lying close to and practically coinciding with the upper 25 right-hand corner of the feed roll; and the angle of the bevel may be varied by adjusting the feed roll angularly about a horizontal axis passing through this corner, said adjustment adjusting at the same time all of the work-engaging parts 30 of the machine, except the knife which remains always in the angular position shown but may be adjusted vertically.

It has been explained that the rear edge 49 of the supporting table lies in a vertical longitudinal plane passed through the axis of the feed roll (that is, in register with the uppermost element of the feed roll). In order to control the work properly, particularly in skiving curved edges, the rear wall 61 of the presser foot 17 (Fig. 40 6), as well as the rear wall 63 of the edge gage (Fig. 7), also lies in this same plane, and the lower corner *x* of the presser foot and the lower corner *y* of the edge gage are in line. In order to control and properly guide the severed strip 300 (Fig. 4) while maintaining the structure just above described, a strip controller is provided which telescopes with the edge gage in a direction transverse to the direction of feed of the work so that the edge gage may be adjusted to 45 provide for cutting off strips of different widths. To this end the presser foot 17 (Fig. 5) carries a strip-controller 51 having a substantially quarter-round cross-section (Figs. 3, 5) which is adapted to be received slidably in a correspondingly shaped socket or recess 53 in the stem 55 of the edge gage 19, the cross-section of the recess 53 (Fig. 3) being somewhat larger than the cross-section of the controller 51 to permit the controller to rise and fall with the presser foot. 50 The controller 51 (Fig. 5) has a stem 57 which is received in a rabbet in the rear of the upper portion of the presser foot and is fastened to the presser foot by screws one of which is shown at 59 in Fig. 6. When the presser foot and 55 edge gage are assembled in the machine, their rear walls 61, 63, as has been stated, are in line and are located in a vertical longitudinal plane passed through the axis of the feed roll.

Referring now more particularly to Figs. 1 and 70 3, the mounting of the presser foot and edge gage will be described. The presser foot 17 and its mounting are substantially the same as in the patented machine. The stem 65 of the presser foot is slidable in a vertical bore in the outer 75 end of a bracket 71 which is mounted for hori-

zontal adjustment on the bracket 33 by means of a cap screw 73 which passes through a slot 75 in the bracket 33 and is threaded into the bracket 71. A bell-crank lever 77 pivoted at 79 to the bracket 71 has a substantially horizontal arm, which extends into a vertical slot 81 (Figs. 2 and 5) in the stem of the presser foot, and an upwardly extending arm having a bore into which an adjusting screw 83 is threaded. A compression spring 85 has its right-hand end (Fig. 1) located in a socket in the bracket 71 and receives in its left-hand end a reduced end of the screw 83. This spring normally holds the presser foot 17 down as far as is permitted by a nut 87 which is threaded upon the reduced upper end of the 15 stem 65 of the presser foot.

The lower face of the bracket 71 has a tongue 89 (Fig. 3) which is received in a groove formed in the upper face of a block 91, said block being fastened to the bracket 71 by screws, one of which is shown at 93, and having a downwardly projecting portion through which extends a guideway 95 rectangular in cross-section in which is slidably received the stem 55 of the edge gage 19, said stem being held in adjusted position by 20 a thumb screw 97. The edge gage 19 may thus be adjusted horizontally, the controller 51 extending more or less into the recess 53 in the edge gage as said edge gage is adjusted.

The machine has been described above with 30 reference to cutting off vamps or other pieces of work on a bevel. It may be used also for regular skiving, that is for beveling the margin of a shoe part or other piece of sheet material. In such case, the edge gage 19 is adjusted up 35 to the right-hand edge of the feed roll as viewed in Fig. 1, or partly across the periphery of the feed roll. In the latter case, if desired, the supporting table 21 which normally projects from .005 to .007 of an inch beyond the periphery of 40 the feed roll may be lowered; and the bracket 33 may also be lowered to cause the curved face of the edge gage to lie close to the periphery of the feed roll.

For regular skiving, it is desirable to provide 45 an auxiliary edge gage in order to furnish means for readily producing a different sort of scarf. To this end an auxiliary edge gage 99 is provided (Fig. 1) the right-hand end of its stem 101 extending between the arms of a fork at the right-hand end of a bracket 103 and being pivoted about a small screw 105 which passes loosely through one arm of the fork and through the stem and is threaded into the other arm of the fork. The bracket 103 is adjustably fastened to 55 the block 91 by screws 104 which pass through slots in the bracket and are threaded into the block 91. A compression spring 107 urges the auxiliary edge gage at all times to swing down into operative position. As shown in Fig. 1, the 60 auxiliary edge gage is being held up in inoperative position by a cam 109 pivoted to the block 91 by a screw 111. Between the head of the screw and the cam is a coiled spring 113 (Fig. 3). By 65 swinging the cam down the auxiliary edge gage may be permitted to swing down into operative position. When the auxiliary edge gage is down in operative position, it is possible to push the edge of the work beneath it and use the regular edge gage 19 or to use the auxiliary edge gage as 70 may be desired.

Having thus described my invention, what I claim as new and desire to secure by Letters Patent of the United States is:

1. A machine for cutting on an angle a strip 75

from a piece of flexible material having, in combination, a rotary feed roll, a member for supporting the strip which is to be cut off, a presser foot for holding the body portion of the material against the feed roll, a knife, a controller for the strip carried by the presser foot and extending over the supporting member, and an edge gage adjustable toward and from the presser foot, said edge gage having a recess into which the controller extends more or less in accordance with the adjusted position of the edge gage.

2. A machine for cutting on an angle a strip from a piece of flexible material having, in combination, a rotary feed roll, a member for supporting the strip which is to be cut off, a presser foot for holding the body portion of the material against the feed roll, the rear wall of said presser foot being located substantially in a vertical longitudinal plane passed through the axis of the feed roll, a controller for the strip carried by the presser foot and having its rear wall in front of said plane, a rotary disk knife the forward point of which lies close to said plane, and an adjustable edge gage having its rear wall lying in said plane and having in it a recess or socket into which the controller extends.

3. A machine for cutting on an angle a strip from a piece of flexible material having, in combination, a feed roll, a bearing in which the feed roll shaft is rotatable, a knife, a presser foot for holding the body portion of the work against the feed roll, an edge gage, a member for supporting the strip which is to be cut off, a controller extending over the strip-supporting member, and means for mounting said member on the feed roll bearing for adjustment longitudinally of the feed roll axis, toward and from the controller and forward and back in the direction of feed movement of the work.

4. A machine for cutting on an angle a strip from a piece of flexible material having, in combination, a feed roll, an angularly adjustable bearing in which the feed roll shaft is rotatable, a knife, a presser foot for holding the body portion

of the work against the feed roll, an edge gage, a member for supporting the strip which is to be cut off, a controller extending over the strip-supporting member, and means for mounting said member on the feed roll bearing for adjustment longitudinally of the feed roll axis, toward and from the controller and forward and back in the direction of feed movement of the work.

5. A machine for cutting on an angle a strip from a piece of flexible material having, in combination, a rotary feed roll, a member for supporting the strip to be cut off, said member having a supporting face curved to correspond to the curvature of the feed roll and projecting beyond the periphery of the roll so as to impart a bend to the material, a presser foot for holding the body portion of the material against the feed roll, a controller for the strip carried by the presser foot, and a knife arranged to sever the material at the bend.

6. A machine for cutting on an angle a strip from a piece of flexible material having, in combination, a rotary feed roll, a member for supporting the strip which is to be cut off, a knife inclined to the axis of the feed roll, a presser foot for holding the body portion of the material against the feed roll, and a controller for the strip having an operative face located above the level of that of the presser foot, said controller extending over the strip-supporting member and being carried by the presser foot.

7. A machine for cutting on an angle a strip from a piece of flexible material having, in combination, a rotary feed roll, a stationary member for supporting the strip which is to be cut off, said member having a supporting face curved to correspond to the curvature of the feed roll, a knife inclined to the axis of the feed roll, a presser foot for holding the body portion of the material against the feed roll, and a controller for the strip having an operative face located above the level of that of the presser foot, said controller extending over the strip-supporting member and being carried by the presser foot.

CLIFTON T. BATCHELDER. 45
